UNITED STATES PATENT OFFICE.

HUGO BANSEN, OF FRIEMERSHEIM, GERMANY.

GAS BURNER.

Application filed August 5, 1926, Serial No. 127,228, and in Germany March 5, 1923.

My invention relates to gas burners such as are used for example in metallurgical furnaces and boilers. More particularly my invention relates to improvements in burners 5 of the type in which the fuel and the air for supporting combustion are delivered into the mixing chamber respectively in axial and tangential direction, and in which a plurality of tangential nozzles are provided. 10 The object of the improvements is to provide a burner of this type in which gas and fuel are intimately mixed, and in which the axial and tangential jets of fuel completely permeate each other, so that the whole mass of 15 gas is subject to the intermingling process. With this object in view my invention consists in providing the burner with a plurality of tangential nozzles as well as with a plurality of axial nozzles. I have found that by thus thoroughly intermingling the jets of gas a jet of the mixture is produced 20 which has a whirling motion resulting in a developed flame having a comparatively short zone in which the flame is formed. 25 For the purpose of explaining the invention two examples embodying the same have been shown in the accompanying drawing in which the same letters of reference have been used in all the views to indicate corresponding parts. In said drawing, 30 Fig. 1, is a diagrammatical perspective view showing the burner and illustrating the delivery of the jets of gas and air into the mixing chamber, 35 Fig. 2, is a diagrammatical elevation illustrating the forming of the flame, Fig. 3, is a sectional elevation taken on the line 3—3 of Fig. 4 and showing the burner, 40 Fig. 4, is a sectional elevation taken on the line 4—4 of Fig. 3, Fig. 5, is a sectional elevation taken on the line 5—5 of Fig. 6 and showing a modification of the burner, and 45 Fig. 6, is a sectional elevation taken on the line 6—6 of Fig. 5.

In the example shown in Figs. 3 and 4 the burner comprises a combustion chamber *a* and a mixing chamber *b* of cylindrical form. At the rear of the mixing chamber *b* 50 there is a chamber *c* having an axial supply *g* for air or gas and communicating with the mixing chamber *b* through nozzles or holes *d* disposed parallel to the axis of the burner. Further the mixing chamber is provided with inlet openings or nozzles *e* disposed tangentially of the said chamber. In the operation of the burner one of the fluids, for example gas, is delivered into the mixing chamber from the chamber *c* and through the nozzles *d* and in axial direction, while the other fluid, in the present case air for supporting combustion, is delivered into the mixing chamber in tangential direction. Therefore the jets of gas and air impinge on each other in the manner illustrated in Fig. 1, Fig. 2 showing the whirling motion of the mixture delivered into the combustion chamber *a*.

In the modification shown in Figs. 5 and 6 the chamber *a'* has a cylindrical rear extension, and a tubular member *f* extends concentrically into the said rear extension thus forming an annular mixing chamber *b'*, the tubular member *f* being provided with a flange *h* by means of which it is secured to the wall of the mixing chamber *b'*. The tubular member *f* is closed at its inner end *i*, and it is provided with circumferential holes or nozzles *e'*, opening tangentially into the mixing chamber *b'* as is best shown in Fig. 5. The tubular member *f* is extended outwardly so as to provide an annular chamber *k*, which chamber communicates with the annular chamber *b'* through nozzles or bores *d'* made in the flange *h* and disposed parallel to the axis of the burner. In the operation of the burner gas and air are delivered into the mixing chamber *b'* where they are intimately mixed, the mixture passing into the combustion chamber *a'* having a whirling motion.

I claim:

1. A burner comprising a circular mixing chamber having a plurality of inlet openings disposed parallel to the axis of said mixing chamber, and having a plurality of inlet openings disposed tangentially to the axis of the chamber, and a fuel supply for said parallel and tangential openings, so that the flow of fuel and air through said parallel and tangential openings will impinge each other at an angle.
2. A burner comprising a circular mixing chamber having a plurality of inlet openings disposed parallel to the axis of the chamber, and adjacent its inner periphery, and having a plurality of inlet openings disposed tangentially to the axis of the chamber.

ber, and a fuel and air supply for said parallel and tangential openings, so that the flow of fuel and air through said parallel and tangential openings will impinge each other at an angle.

3. A burner comprising a circular mixing chamber, having a plurality of inlet openings adjacent its inner periphery, and disposed parallel to the axis of the chamber and having a plurality of inlet openings in the periphery of the mixing chamber and disposed tangentially to the axis of the mixing chamber, and a fuel and air supply for said parallel and tangential openings, so that the flow of fuel and air through said parallel and tangential openings will impinge each other at an angle.

4. A burner comprising a circular mixing chamber having one end open and the opposite end closed, the closed end of the mixing chamber having a plurality of inlet openings disposed parallel to the axis of the chamber, and the periphery of said chamber having a plurality of openings disposed tangentially to the axis of said chamber, and a fuel and air supply for said parallel and tangential openings, so that the flow of fuel and air through said parallel and tangential openings will impinge each other at an angle.

5. A burner comprising a circular mixing chamber having a plurality of inlet openings disposed parallel to the axis of the chamber and having a plurality of inlet openings disposed tangentially to the axis of the mixing chamber so that the flow of fuel and air through said parallel and tangential openings will impinge each other at right angles.

6. A burner comprising a circular mixing chamber having a plurality of parallel inlet openings parallel with the axis of the mixing chamber and having a plurality of inlet openings disposed tangentially to the axis of the mixing chamber, and said tangential and parallel openings arranged so that the supply of fuel and air through the openings

will impinge each other and cause a whirling of the mixture in the chamber.

7. A burner comprising a circular mixing chamber having a transverse partition intermediate its ends, said partition having a plurality of parallel openings arranged parallel with the axis of the chamber, a central supply for said space formed by the partition and the outer periphery of said mixing chamber having a plurality of openings arranged tangentially to the axis of the mixing chamber, and the jets of air and fuel passing through said openings adapted to impinge each other and cause a whirling of the mixture in the mixing chamber.

8. A burner comprising a circular mixing chamber having a plurality of inlet openings disposed parallel to the axis of the chamber, and having an inlet opening disposed tangentially to the axis of the mixing chamber for each parallel opening so that the flow of fuel and air through said parallel and tangential openings will impinge each other at an angle.

9. A burner comprising a circular mixing chamber having a plurality of inlet openings disposed parallel to the axis of the chamber and close to the inner periphery thereof, and having a plurality of inlet openings disposed tangentially to the axis of the mixing chamber so that the flow of fuel and air through said parallel and tangential openings will impinge each other at an angle thereto.

10. A burner comprising a mixing chamber having a plurality of inlet openings disposed parallel to the axis of the chamber and close to the inner periphery of the chamber, and an inlet opening disposed tangentially to the axis of the mixing chamber for each parallel opening so that the flow of fuel and air through said parallel and tangential openings will impinge each other at an angle thereto.

In testimony whereof I hereunto affix my signature.

HUGO BANSEN.
